UNITED STATES PATENT OFFICE.

WILLIAM F. SCHULTHEISS, OF LOS ANGELES, CALIFORNIA.

DIVERSION VALVE.

Application filed September 7, 1926. Serial No. 133,954.

This invention relates generally to a valve used for diverting water to either of two outlets, and commonly used in connection with a bath tub and shower.

5 The primary object of this invention is to provide a valve structure of simple and economical construction having a single operating member easily assembled, and disassembled to permit replacement of parts.

10 These objects together with other objects and corresponding accomplishments are obtained by means of the embodiments of my invention illustrated in the accompanying drawing, in which:

15 Fig. 1 is a vertical sectional view of a complete valve, parts thereof being shown in elevation; and Fig. 2 is a section seen on the line 2—2 of Fig. 1.

Referring with more particularity to the drawing, a valve casing is indicated by 3. This casing has a cylindrical wall forming a plunger barrel 4, and at one end thereof is an end wall 5 having a valve port 6 therein. The bore of the barrel opens through 25 the casing and is internally threaded as indicated by 7 to receive a cap 8. In the side wall of the barrel is a port 9 communicating with an outlet chamber provided with an outlet 10 connected to one of the fixtures to be supplied with water. The barrel 4 forms 30 an inlet chamber to which inlets 11 and 12 are connected, one for hot water and the other for cold water. Port 6 communicates with an outlet chamber having an outlet 13 35 communicating with the other fixture to which water is to be supplied.

The cap 8 is provided with an internal thread for engagement by a thread on a stem. Mounted over the tubular extension 40 of the cap 8 is a gland nut 14 provided with packing for suitably packing the stem 15. The stem is provided with an enlarged portion 16 having a thread corresponding to the thread in the cap, and at the inner end is 45 mounted a valve 17 provided with a washer to seat over the port 6, and the valve is dimensioned to permit water to pass therethrough when it is unseated. Slidably mounted within the barrel and fixed to the 50 stem 15 is a plunger 18 having perforations or holes 19 extending therethrough to permit water to pass from one side to the other of the plunger. It will be noted that there 55 is a bevelled edge on the cap 8 adapted to receive a corresponding portion of the

plunger 18 and so positioned that when the valve stem is operated to bring the plunger 18 against the cap 8, the valve 17 will be off its seat. At this time the plunger will cover the side wall port 9 and cut off communication between the inlet chamber and the lower outlet chamber. When the valve 17 is on its seat, the plunger 18 will be in such a position as to uncover the port 9.

Assume that the outlet 13 is connected to a shower and the outlet 10 to a bath tub. The inlets 11 and 12 may be connected to hot and cold water pipes for supplying water of the desired temperature. If it is desired to supply water to the shower, valve handle 20 is 65 operated to unseat valve 17 and position plunger 18 against the cap thereby covering side port 9. Water may then pass into the inlet chamber, through the port 6, into the outlet chamber 12 and then to the shower. 70 To supply water to the bath tub, the valve handle is operated to seat valve 17, closing port 6. Port 9 is thereby uncovered by the plunger, and water may pass from the inlet chamber, through the holes 19 in the plunger, 80 through port 9 and to the bath tub.

What I claim is:

1. A valve structure of the character described comprising a casing having a first outlet chamber and a second outlet chamber 85 separated by an intermediate inlet chamber defined by a wall forming a plunger barrel having a valve port at one end communicating with the first outlet chamber, said inlet chamber communicating at the other 90 end with the second outlet chamber, a stem extending into said inlet chamber and being provided with a valve for said valve port, a plunger on said stem separating said inlet chamber and the second outlet chamber, there being a passage for placing said inlet chamber in communication with the second outlet chamber controlled by travel of said plunger whereby when said valve is seated to 95 close the first outlet chamber, said inlet chamber will be in communication with the second outlet chamber and when said valve is moved to its opposite extreme position to open the first outlet chamber, said inlet chamber will be closed from the second outlet chamber.

2. A valve structure of the character described comprising a casing having a first outlet chamber and a second outlet chamber separated by an intermediate inlet chamber 100

110

defined by a wall forming a plunger barrel having a valve port at one end communicating with the first outlet chamber and a passage at the other end communicating with the second outlet chamber, a stem extending into said casing and being provided with a valve for said valve port, a plunger on said stem separating said inlet chamber and the second outlet chamber, said passage being controlled by travel of said plunger whereby when said valve is seated to close the first outlet chamber said inlet chamber will be in communication with the second outlet chamber and when said valve is moved to its opposite extreme position to open the first outlet chamber said inlet chamber will be closed from the second outlet chamber.

3. A valve structure of the character described comprising a casing having a first outlet chamber and a second outlet chamber separated by an intermediate inlet chamber defined by a wall forming a plunger barrel having a valve port at one end communicating with the first outlet chamber and a side port in said wall at the end opposite to said valve port for communication with the second outlet chamber, a stem extending into said casing and provided with a valve for said valve port, a plunger on said stem separating said inlet chamber and the second outlet chamber and arranged to bridge and close said side port, there being a passage through said plunger for liquid to pass from one side of the plunger to the other for placing said inlet chamber in communication with the second outlet chamber whereby when said valve is seated to close the first outlet chamber said inlet chamber will be in communication with the second outlet chamber and when said valve is moved to its opposite extreme position to open the first outlet chamber, said inlet chamber will be closed from the second outlet chamber.

4. A valve structure of the character described comprising a casing having a first outlet chamber and a second outlet chamber separated by an intermediate inlet chamber defined by a wall forming a plunger barrel having a valve port at one end communicat-

ing with a first outlet chamber and a side port in the wall at the end opposite said valve port for communication with the second outlet chamber, a stem extending into said casing and provided with a valve for said valve port, a plunger on said stem arranged to bridge and close said side port, there being a passage through said plunger for liquid to pass from one side of the plunger to the other and whereby when said valve is seated to close the first outlet chamber, said inlet chamber will be in communication with second outlet chamber and when said valve is moved to its opposite extreme position to open the first outlet chamber, said inlet chamber will be closed from the second outlet chamber.

5. A valve structure of the character described comprising a casing having a first outlet chamber and a second outlet chamber separated by an intermediate inlet chamber defined by a cylindrical wall forming a plunger barrel having a valve port at one end communicating with the first outlet chamber and a side port in said wall at the end thereof opposite to said valve port providing for communication between said inlet chamber and said second outlet chamber, a stem extending into said casing and provided with a valve for said valve port, a plunger on said stem arranged to bridge and close said valve port, there being a seat for said plunger in said casing for said plunger to rest thereagainst when the latter bridges said side port, there being a passage through said piston for a liquid to pass from one side to another whereby when said valve is seated to close the first outlet chamber said inlet chamber will be in communication with the second outlet chamber and when said valve is moved to its opposite extreme position to open the first outlet chamber said inlet chamber will be closed from said second outlet chamber.

In witness that I claim the foregoing I have hereunto subscribed my name this 13th day of August, 1926.

WILLIAM F. SCHULTHEISS.
